UNITED STATES PATENT OFFICE.

WILHELM WADLER, OF WEEHAWKEN, NEW JERSEY, ASSIGNOR OF ONE-HALF TO
JOSEPH HOCH, OF WEST HOBOKEN, NEW JERSEY.

GAS AND COAL STOVE.

1,385,597.

Specification of Letters Patent. Patented July 26, 1921.

Application filed May 11, 1920. Serial No. 380,569.

To all whom it may concern:

Be it known that I, WILHELM WADLER, a citizen of the Republic of Hungary, residing at Weehawken, county of Hudson, 5 and State of New Jersey, have invented certain new and useful Improvements in Gas and Coal Stoves, of which the following is a specification.

This invention relates to improvements in 10 combined gas and coal burning stoves and has as its special objects the provision of means whereby gas or coal may be used as fuel for cooking or baking purposes.

One of the objects of the invention is to 15 provide a stove in which the coal, if used as fuel, may be ignited by gas and the draft may be suitably regulated.

Another object of the invention is to provide a stove in which the ashes can be removed 20 automatically by employing a suitable suction means to avoid the dust from entering the kitchen.

A further object of the invention is to provide a stove provided with a baking 25 compartment which can be heated by two sets of gas flames simultaneously in order to create a uniform heat on all sides.

Other objects are the provision of means for storing coal, and for heating water by 30 one or the other of the fuels, and the pre-heating of dishes, etc.

These and other like objects are attained by the novel construction and combination of parts hereinafter described and shown in 35 the accompanying drawings, forming a material part of this disclosure, in which—

Figure 1 is a front elevation of a stove constructed according to the present invention.

Fig. 2 is a top plan view with the top plate in place on the stove.

Fig. 3 is a view similar to Fig. 2 with the top plate removed.

Fig. 4 is a transverse sectional view taken 45 on line 4—4 of Fig. 3.

Fig. 5 is an end view of the stove partly in section.

Fig. 6 is a transverse sectional view taken on line 6—6 of Fig. 1.

Fig. 7 is a detail top plan view of the fire-box after removal of the grate.

Fig. 8 is a detail view of a gas burner employed in connection with my stove.

Fig. 9 is a transverse section through the

burner shown in Fig. 8, taken along line 55 9—9 of Fig. 8.

Fig. 10 is an enlarged view of one of the shaker bars showing the flexible connection for the gas supply.

Referring to the drawings, the numeral 60 10 indicates the stove closed at the front by the customary doors 11 and 12 provided with suitable grasping handles, locking means 14, and hinges. At its lower front part the stove contains a drawer 16, with 65 handles or grips 17 for the storing of coal if such is to be used as fuel.

The gas is supplied to the stove through a suitable conduit 18 adapted to be connected to any gas supply pipe.

A water tank 19 having an exhaust 79 is arranged on top of the rear part of the stove and the water contained therein is heated by gas, if such is used as fuel, supplied through pipes 20. The water is filled into 75 the tank through the top thereof. Shelves 21 or the like are provided in compartments 22 on top of tank 19 for the storage of dishes to be preheated or warmed and which are closed at the front by suitable sliding 80 doors 23.

An auxiliary water tank 24 is provided on one side of the stove where the fire box is located.

The rear of the stove shows the customary 85 socket 25 for connection with the well known pipes leading to the chimney.

The stove is provided on top with the ordinary cover plate having a plurality of 90 cooking or fire holes 27.

One of these holes is provided with a bottom 28 and suitable side walls to form a chamber for the reception of steaming water for cooking breakfast food such as for instance, cereal dishes, etc.

This hole is covered by a cover 29 hinged to the top of the stove which has the usual 95 centrally located pot-hole.

As shown in Fig. 3 the stove is chambered and in the central chamber a gas burner 30 is 100 located which is more fully illustrated in Figs. 8 and 9. This burner is ring shaped and is provided at its upper, as well as its lower face with a plurality of nipples 31 so as to heat a vessel or pot within hole 105 27 and cover the upper wall 32 of a baking chamber 33 below said burner.

The fire box 34 shows the customary re-

volving grate 35 consisting of two grate bars 36, and 37, each having a plurality of side bars 38. The front ends of the bars 36 and 37 carry a pair of gears 39 and 39', adapted to be operated in the well known manner from a central gear 40 provided with a projecting operating stem 41 for the engagement by a suitable operating tool.

The grate bars 36 and 37 are adapted to be vertically displaced within vertical slots 42' of a bracket 42 secured to the inner upper wall of the fire box and are journaled within a frame 43 normally resting with each corner upon a flat curved spring arm 45 secured to horizontal rods 44 transversely arranged within the fire box and adapted to make one half revolution with these rods. The outer ends of the rods 44 are passed within suitable sleeves 46 through the tank 24 and extend beyond the outer wall of the stove, where they carry other curved arms 47 similarly shaped as the arms 45, the free ends of which are connected by a rod 48 adapted to be operated by a knob 49 to execute one half revolution in one or the other direction, in order to raise or lower the grate and its frame within certain limits, as will be clearly understood for a purpose hereinafter more fully described.

Below the grate an ash receiver 50 is secured upon an axle 51 journaled within the rear and front walls of the stove and the front end of said axle is extended beyond the outer wall of the stove and is shaped as at 52 to adapt it for engagement by a suitable tool for revolving the receiver 50 which has the shape of a basket, the side and bottom walls of which constitute a screen 53.

In order to assist the screening operation of the ashes falling through the grate the top of the ash receiver is formed by a plurality of slats 54, transversely arranged within the receiver as shown.

The single slats 54 are each provided with an upwardly extending arm 55, and the upper ends of these arms are secured to a common operating rod 56 adapted to be operated by a suitable hook or tool engaging a hole 57, in the front end of said rod 56 for imparting to the rod 56 a reciprocatory movement to operate the slats 54 to regulate the draft. This rod has preferably the form of a gas pipe and is provided at its upper face with a plurality of gas nipples covered by a protector 80. A flexible tube 78 connects the rod 56 to a gas supply pipe.

The shaft 51 carries at its rear end between the rear wall of the stove and the rear wall of the ash receiver 50, a sprocket wheel 58 on which a chain or the like 59 is guided, which is also guided over a sprocket wheel 59' on the shaft 60 of a fan 61 for a purpose to be hereinafter more fully described.

Beneath the revolving ash receiver 50 an ash pan 62 is provided having a central

opening in alignment with a similar opening 63 in the stove bottom through which the ashes and cinders can fall into the cellar through an opening 64 in the floor. In case this is not desired, the holes are closed and 70 the pan 62 can be emptied, if required by removing it through the front wall of the stove.

In order to regulate the draft, numerous dampers are arranged at various parts and 75 in the various compartments of the stove. A damper 65 covers an opening 66 of the fan chamber 67 and is operable by a rod provided with an operating rod and knob 68. Another damper 69 covers the opening 80 70 leading from the top of the fan chamber 67 to the central compartment 71 and is operable by an operating rod and knob 72, knobs 68 and 72 are shown at one side of the stove in Fig. 3.

To both sides of the bake oven 73 perforated dampers 74 operable by rods and knobs 75 are located, adapted to regulate the temperature prevailing within the oven, and a damper 76 operable by a rod and knob 90 90 77 is provided to regulate the temperature on top of the bake oven.

In operation either gas or coal may be used as fuel, the former being supplied through the conduit 18 in the customary 95 well known manner, while the coal stored in drawer 16 is piled upon the grate and ignited by the ignition of the gas jets in the bar on top of the ash receiver, which are suitably protected in order to avoid choking 100 of the same, by dust or ashes.

The bake oven 73 is heated by gas from a suitable burner 73' (Fig. 6) below its bottom and from the gas jets on the under- 105 side of burner 30.

If required the various dampers are suitably operated to regulate the draft and consequently the heat in the various compartments.

When coal is used as fuel the grate is 110 from time to time operated in the usual manner by a suitable tool so that the ashes will be sifted while simultaneously the fan 61 is operated to suck the developing dust out of the fire box into the socket 25 leading 115 to the chimney.

It will be clear that changes can be made in the form and shape and general arrangement of the parts constituting the stove in accordance with the present invention without departing from the scope or spirit of my invention, but what I claim, and desire to secure by Letters Patent is—

1. A stove of the character described comprising in combination, a chambered body, 125 a plurality of flues in said body, means for connecting said flues with a chimney, means for controlling said flues, a fire box constituted by one of the stove chambers, a revolving grate in said body, a frame for said 130

grate, a means for raising and lowering said frame and grate, an ash receptacle below said grate, a plurality of slats transversely arranged within said receptacle, a sieve 5 formed with the side and bottom walls of said receptacle, a plurality of shaker bars disposed in said receptacle, a common operating rod for said slats, constituting a gas burner, means for supplying gas to 10 said burner, a shaft for said receptacle journaled in the rear and front wall of the stove, a sprocket wheel on said shaft, and a fan operated from said shaft and sprocket wheel during the sifting operation for removing 15 the dust.

2. A stove of the character described, comprising in combination, a chambered body, a plurality of flues, connecting the chambers of said body, dampers for controlling the flues and the temperature within said 20 chambers, means for burning coal in said stove, means for burning gaseous fuel, an ash sifter revolubly arranged in the fire box of said stove, a fan for preventing the spreading of dust to the outside of the 25 stove, means for operating said fan, an operating rod for closing said sifter constituting a gas burner, and a flexible connection between said pipe and a gas supply, substantially as described and for the purpose set forth.

In testimony whereof I have affixed my signature.

WILHELM WADLER.
